UNITED STATES PATENT OFFICE.

FRANK W. PETERSON, OF HARCOURT, IOWA.

DESIGN FOR A MANURE-HOOK.

46,579.

Specification for Design.

Patented Oct. 20, 1914.

Application filed August 31, 1914. Serial No. 860,121. Term of patent 14 years.

To all whom it may concern:

Be it known that I, FRANK W. PETERSON, a citizen of the United States, residing at Harcourt, in the county of Webster and State of Iowa, have invented a new, original, and ornamental Design for Manure-Hooks, of which the following is a specification, reference being had to the accompanying drawing, forming part thereof.

The figure shows a perspective view of a manure hook, embodying my invention.

I claim:

The ornamental design for a manure hook, as shown.

Des Moines, Iowa, August 29, 1914.

FRANK W. PETERSON.

Witnesses:

WILL FREEMAN,
L. ROBINSON.
